APPARATUS FOR ESTABLISHING A VACUUM
IN MANOMETER-TYPE INSTRUMENTSCharles F. Wallace, Westfield, N. J., assignor to
Wallace & Tiernan Products, Inc., Belleville,
N. J., a corporation of New Jersey

Application September 14, 1944, Serial No. 554,098

3 Claims. (Cl. 73—1)

1

The present invention relates to an apparatus for establishing and maintaining a desired vacuum above a column of liquid in manometer type instruments, such, for example, as mercury barometers and more particularly to the apparatus for introducing the liquid into the column and establishing thereabove a desired and substantially perfect vacuum.

In apparatus such as mercury barometers, for example, it has been necessary in order to obtain the desired vacuum above the mercury, to fill the glass tube completely with mercury and then by holding the same closed, possibly by thumb of the operator over the end thereof or by the use of some other closure, to invert it and introduce the open end into a bath of mercury in a container arranged to be associated with the lower end thereof. This is inconvenient, to say the least, particularly with sensitive scientific instruments of the type to which the present invention is applicable. Furthermore, there is always the danger of a bubble of air getting into the mercury above the closure when the tube is first filled, so that when it is inverted, this bubble will rise to the upper closed end of the tube and prevent the establishment of the desired vacuum. The same difficulty may also arise if the vacuum is destroyed or diminished for any reason and it is desired to reestablish a desired vacuum. The structure of the present invention and the methods herein-after set forth for using that structure provides a simple and efficient solution for these problems. The provision of such apparatus is, therefore, a principal object of the present invention.

A further and more detailed object of the present invention is to provide a device whereby dirt or other foreign matter of a relatively lower specific gravity than that of the liquid (usually mercury) may be kept out of the mercury in the column, the height of which is to be determined, thus enabling more accurate readings to be made than could be done if this foreign matter was allowed to remain and float upon the surface of the liquid.

Other objects and advantages of the present invention will become apparent from the following specification and appended claims when taken in connection with the accompanying drawings, in which:

Figure 1 is a view principally in elevation, but with parts broken away and in central vertical section showing a mercury barometer constructed in accordance with the present invention, the view being foreshortened for space requirements on the drawing; and

2

Fig. 2 is a detail view substantially in horizontal section on line 2—2 of Fig. 1.

While the present invention is applicable to manometers of various types and further may be employed with liquids other than mercury, I have chosen to illustrate the invention as applied to a mercury barometer.

Turning now particularly to the drawings, there is shown a barometer including a base 1, which may be formed as a mercury containing chamber and which is provided with a cover 2 adapted to be secured thereto in any suitable manner as by screws 3, the joint between the base 1 and the cover 2 preferably being made air-tight in any usual manner. Secured to the cover 3 are a plurality of posts 4, which support and are tied together at their upper ends by a plate 5. This plate is adapted to support the upper end of a tube 6, preferably of glass, in which is a liquid 7 such as mercury, the level of which is shown at 8 and is indicative of a gaseous pressure being measured. This pressure is communicated to the upper portion of the chamber within the base 1 through a flexible tube 9 and an angle fitting 10, it being understood that the tube 6 extends down below the surface of the bath of mercury within the chambered portion in the base 1 in the usual manner. A suitable scale 11 having desired graduations thereon as shown may be secured to the cover 2 and the plate 5 in any suitable manner not particularly illustrated in the drawings, but which will be obvious to those skilled in the art.

A conventional filling opening may be provided 35 in the cover 2 and closed by a screw plug 12. It will be understood that mercury (or other liquid) may be introduced into the body thereof within the base 1 and the opening thereafter closed by the plug 12.

Means are provided for supporting the tube 6, such means in the present instance including the provision of a reduced diameter extension 13 at the upper end thereof which passes through and in frictional supporting relation with a resilient member 14 such as a cork, the outside of which is tapered and is received in a similarly tapered hole in a supporting plate 15, which is in turn supported from the plate 5 through legs 16, which may, if desired, be integral therewith.

In devices of this kind, it is necessary that a substantially perfect vacuum be maintained in a space 17 at the upper end of the tube 6 above the level 8 of the liquid 7 therein. The present invention provides apparatus and methods for establishing this vacuum. For this purpose there

is provided within the reduced upper extension 13 of the tube 6 an upper chamber 18 closed at its upper end by a suitable closure 19 and communicating with the space 17 through a constricted passage 20. Arranged concentrically with the tube 6 and the extension 13 thereof is a valve comprising a cylindrical stem 21 adapted to extend entirely through the constricted passage 20 and to maintain therewith a mercury-tight seal. The stem 21 extends upwardly through the closure 19 and has secured to the upper end thereof an operating knob 22. A suitable gland packing means indicated generally at 23 is provided for preventing leakage around the valve stem 21 and for maintaining the valve stem against undesired movement by providing a frictional engagement therewith of the packing, which may be suitably compressed in the usual manner as shown. The underside of the closure 19 may be provided with a suitable counter-bore 24, communicating through a lateral bore and a fitting 25 with a flexible tube 26, which is adapted to be connected to a suitable source of vacuum (not shown).

When it is desired to initiate the operation of the apparatus just described, the valve 21 is opened by pulling the knob 22 vertically upwardly. The apparatus as a whole may then be tipped sufficiently to reduce the vertical distance between the surface of the liquid within the body thereof in the base 1 and a point part way up the upper chamber 18 to permit the liquid level to be raised as hereinafter set forth. A differential pressure is then applied to the opposite ends of the liquid, that is, to the surface of the liquid within the base 1 outside the tube 6 on the one hand and that within the tube 6 on the other, so as to cause the liquid 7 to rise in the tube 6 through the passage 20 and in the chamber 18 up to a point within the upper chamber such as the level 27. Thus there will be a body of the liquid 28 in the upper chamber above the passage 20. The knob 22 is then moved downwardly to move the valve stem through the passage 20, thus effecting a mercury-tight seal at this point. Then the differential pressure may be relieved and the apparatus as a whole righted to its normal vertical position. At this time the liquid 7 within the tube 6 will attain its equilibrium level, which may be at the level 8 as shown, so that there will be produced a vacuum in the space 17 between the level 8 and the upper end of the tube 6, that is, up to the constricted passage 20. At the same time, a part of the liquid 28 will be retained above the constricted passage to a level such as shown at 27. Downward flow of this liquid into the body thereof within the tube 6 will be prevented by the valve stem closing the passage 20. Here, however, the seal need only be tight as to flow of the liquid, so that even though this valve might not fit tight enough to form an air-tight or vacuum-tight seal, it prevents the liquid flowing down through the passage 20 so that the desired result is attained.

While I have just described the movement of the liquid up into the upper chamber by the application of a differential pressure, it will be understood that this differential pressure may be obtained either by applying a super-atmospheric pressure through the tube 9 into the interior of the chamber formed in the base 1 or by applying a suitable vacuum through the tube 26 to the chamber 18 or by some combination of the two. In the event that a super-atmospheric pressure is applied through the tube 9 sufficient to cause

an upward flow of the liquid into the upper chamber or at least up to the passage 20, it will be unnecessary to tilt the apparatus as a whole as just described. Even if some pressure is applied through the tube 9 so that the necessary vacuum which is applied through the tube 26 in addition to the pressure applied in order to obtain the necessary differential will cause the liquid to rise as aforesaid, this tilting need not be done.

However, I have found it extremely desirable to apply a vacuum through the tube 26, even though it may involve additional mechanical manipulation. The reason for this may be exemplified in the following way. Let us suppose for example, that it is desired to maintain in the space 17 a vacuum equivalent to one-one-thousandth of an atmosphere pressure. If now a tiny bubble of air were by some inadvertence trapped within the tube 6 when the level of the liquid was raised as aforesaid so that this bubble did not pass upward through the passage 20 and exhaust above the level of the liquid, then if the liquid were being raised by pressure applied through the tube 9 and the bubble were formed at atmospheric pressure, the air in this bubble would expand about a thousand times upon the liquid attaining its equilibrium level. This would make a substantial difference in the degree of vacuum resulting from the operation. If, on the other hand, the liquid were caused to rise through the tube 6 and the passage 20 by the application of vacuum to the tube 26 and a vacuum equivalent to one-one-thousandth of an atmosphere pressure were applied, which can be done by a good vacuum pump, then any bubble of air trapped above the liquid would be at the pressure at this point, which would be one-one-thousandth of an atmosphere pressure. If then the operation were completed as hereinabove taught, this bubble would not substantially interfere with the establishment of the desired vacuum as the air of the bubble would be at such an extremely low pressure that it would make practically no difference in the degree of vacuum attained.

Another advantageous result of the operation of the device just described, and in accordance with the method set forth, is that in the event that any foreign material, which is usually of a lower specific gravity than that of the liquid being employed (usually mercury), such foreign material may be removed from that portion of the apparatus within the tube 6, where it is desired to obtain an accurate reading, by the normal operation of renewing the vacuum as just set forth. This is due to the fact that such foreign material will float upon the liquid due to the relative specific gravities of the foreign material and the liquid. Thus when the valve is open and the liquid raised to a level as shown at 27, the foreign material will pass upwardly through the passage 20 and will float upon the body 28 of the liquid in the upper chamber 18 where it will do no harm. If then, the operation is completed as explained hereinabove, that portion of the liquid within the tube 6 will be clean and have a clean surface, the level of which may be easily read in any desired manner.

The type of valve particularly shown in the accompanying drawings, including a substantially cylindrical stem which may be of considerable diameter as shown, is particularly advantageous in order to obtain clearance for the passage of foreign material as just explained, for if the passage 20 were very fine, such material might not pass through it when the liquid is moved up-

wardly into the upper chamber. I contemplate, however, that any suitable type of valve which will be fluid-tight, may be used to close off the passage between the upper chamber and the interior of the tube 6. Many modifications of suitable valves will occur to those skilled in the art.

While there is shown and described herein but one apparatus embodiment of the invention and but a few possible methods of operation thereof, further modifications may be resorted to within the spirit and scope of the appended claims, which are to be construed validly as broadly as the state of the prior art permits.

What I claim is:

1. In an instrument of the manometer type for the determination of gaseous pressures by the height of a liquid column in a tube at the upper part of which a substantial vacuum is maintained, in combination, means forming an upper chamber adjacent to the upper end of said tube, a passage communicating between said upper chamber and the upper end of said tube, valve means operable from outside the apparatus for controlling communication through said passage, and means for applying a differential pressure to the opposite ends of said liquid column.

2. In an instrument of the manometer type for the determination of gaseous pressures by the height of a mercury column in a tube at the upper part of which a substantial vacuum is to be maintained, and wherein a mercury chamber is provided at the lower end of said tube arranged to be exposed to a gaseous pressure to be determined, in combination, means forming an upper chamber communicating with the upper portion of said tube, means adapted to com-

municate between said upper chamber and a source of vacuum, means forming a passage between said upper chamber and the upper portion of said tube, and valve means operable from outside said apparatus to open and close communication through said passage between said upper chamber and the upper part of said tube, the aforementioned parts being so constructed and arranged that when it is desired to establish a vacuum in the upper portion of said tube, the entire instrument may be tilted to reduce the vertical distance between the pool of mercury and the upper end of the apparatus, a vacuum may then be applied to said upper chamber with said valve open and the mercury drawn up until a portion thereof is in said upper chamber and said tube, said passage and at least a part of the upper chamber are filled with mercury, said valve may then be closed and the apparatus brought back to its normal vertical position, so that the mercury in said tube will attain its equilibrium level with a vacuum thereabove and a small portion of mercury is maintained in said upper chamber.

3. Apparatus in accordance with claim 1 wherein in said tube, said upper chamber and the passage forming means therebetween are all constructed integrally of glass, and wherein said upper chamber is above and in substantially vertical alignment with said tube, and further wherein said valve is formed as a cylindrical stem movable axially of said upper chamber and said tube and forms a mercury-tight seal with the wall of said passage.

CHARLES F. WALLACE.
